UNITED STATES PATENT OFFICE.

OLIVER E. BARTHEL, OF DETROIT, MICHIGAN.

MUFFLER.

SPECIFICATION forming part of Letters Patent No. 756,203, dated April 5, 1904.

Application filed November 14, 1903. Serial No. 181,129. (No model.)

To all whom it may concern:

Be it known that I, OLIVER E. BARTHEL, a citizen of the United States of America, residing at Detroit, in the county of Wayne and State of Michigan, have invented certain new and useful Improvements in Mufflers, of which the following is a specification, reference being had therein to the accompanying drawings.

This invention relates to improvements in devices for deadening or muffling the noise caused by the escape or discharge of the exhaust of engines into the open air; and its object is to provide a simple, cheap, and very efficient device for the purpose, having certain other new and useful features and the particular construction and combination of parts, all as hereinafter more fully described, reference being had to the accompanying drawings, in which—

Figure 1 is a longitudinal section of a device embodying the invention, and Figs. 2, 3, and 4 are similar views showing modified constructions.

A represents the exhaust-pipe of an engine, and B the casing of the muffler, consisting of a cylindrical body portion 1, formed of sheet metal, and two opposing heads 2 and 3, formed with short inwardly-projecting flanges 4, to engage the outer side of the sheet-metal body. The head 2 is formed conical, with an inlet-opening 5 at the apex or axis, which is screw-threaded to receive the screw-threaded end of the exhaust-pipe A, and the head 3 is provided with an axial screw-threaded opening 6 to receive the screw-threaded end of the tubular exhaust member 7, which is provided with openings 8 in its sides. A circular deflector-plate 9 is formed conical and at its back or concave side is provided with a screw-threaded socket to receive the opposite screw-threaded end of the exhaust member 7. The deflector is supported within the casing at a short distance from the head 2, with its conical side opposing the inlet-opening and its apex in the axis of said opening, by bolts 10, secured in openings in the deflector, which extend through openings in the head 2 and are provided with nuts 11 on their outer ends, which when turned up against the outer face of the head draw the deflector toward the

head, and as the deflector is attached to the opposite head 3 by means of the exhaust member said heads will be drawn firmly against the ends of the body and the parts all held firmly in position. The deflector forms a wall 55

dividing the space within the casing into two chambers 12 and 13 of unequal capacity, the casing being so proportioned relative to the size of the engine-cylinder and exhaust-pipe that the chamber 12, together with said pipe, 60 has greater cubic capacity than the cylinder, and the capacity of the chamber 13 is several times that of the chamber 12. These chambers communicate with each other through a restricted passage 14 at the periphery of the 65 deflector, the diameter of the deflector being slightly less than the inside diameter of the casing; but as the diameter of the deflector is so much greater than the diameter of the inlet or pipe A the area of said passage is approximately equal to that of the inlet, though 70 very narrow. The exhaust upon entering the chamber 12 is moving with great rapidity and force and striking the deflector expends some of its force thereon and is deflected thereby 75 in all directions toward the passage 14, through which it passes into the chamber 13, where it expands before passing out into the atmosphere through the openings in the exhaust-pipe, which is open at its outer end. By reason of the conical form of the deflector it is 80 not vibrated by the impact of the exhaust, and therefore no sound is produced thereby.

By placing the conical deflector, having a large area, squarely in the path of the outgoing 85 exhaust to receive its impact and deflect and divide the same, thus depriving it of much of its force, and by then causing the exhaust to pass through the narrow passage, which has a capacity approximately equal to that of the exhaust-pipe, thus causing it to pass in a thin sheet into the chamber at the opposite end of the deflector with practically an even flow, where it is allowed to expand, the pulsation caused by the sudden expulsion of each succeeding cylinder charge is entirely eliminated, and the exhaust will pass out through the exhaust-pipe with a steady flow, the force of which is again reduced by passing through the 90 openings in the side of said pipe and will not 100

set up vibrations sufficient to produce any disagreeable noise.

In the construction shown in Fig. 2 the deflector 9 is omitted and the head 15, at the 5 exhaust end of the cylinder, is made conical to receive the impact of the incoming charge and deflect the same outward toward the hollow stay-bolts 16, which are substituted for the bolts 10. These stays 16 extend through both heads 10 and are provided with nuts on their outer ends to draw the heads toward each other and clamp the body between. Small openings 17 in the sides of these stays admit the exhaust to their interior, from whence it passes out through 15 their open ends to the atmosphere. These hollow stay-bolts thus form exhaust-passages and also serve to bind the parts together.

Fig. 3 shows a modified form in which the casing is provided with a conical head 15, secured in place by the hollow stay-bolts 16, having the openings 17, and on the head 15 is a screw-threaded flange 18 to receive the screw-threaded end of a tubular member 19, which extends to within a short distance of 20 the opposite head and forms a narrow passage 20. The exhaust-pipe A is extended inward by the extension 21 to within a very short distance of the head 15, with the apex of said head in the axis of said pipe 21. The exhaust 25 entering through the pipes A and 21 strikes the conical head and is deflected thereby down the tubular member 19 and passes out through the passage 20 into the body of the casing, where it expands and passes out through the 30 tubular stay-bolts.

In Fig. 4 is shown a casing formed with a cylindrical body portion engaged at its ends by two flat heads 22 and 23, provided with axial screw-threaded openings, the opening in 40 the head 22 to receive a pipe 24, similar to the pipe 21 in Fig. 3, forming a continuation of the exhaust-pipe, and the opening in the head 23 to receive the screw-threaded end of a tubular exhaust member 25, similar to the 45 member 7 of Fig. 1. The head 22 is formed with an inwardly-extending tubular portion 26 internally screw-threaded at its inner end to receive a screw-threaded flange on the conical deflector 27, and in the sides of said member 50 26 adjacent to the head 22 are formed openings 28 to allow the exhaust to escape laterally after passing through the member 26. A laterally-extending flange 29 on the member 26 extends outward to near the body of the 55 casing to form a narrow passage 30 between its periphery and the wall of the casing. The exhaust entering through the pipe 24 strikes the head 27 and is deflected thereby down the tubular member 26. It then passes out through 60 the small opening 28, thence out through the narrow passage 30 into the body of the casing, where it expands, and then passes out through the openings in the exhaust member 25.

As shown in Fig. 1, 31 is a sheet of asbestos

or other suitable material which is wrapped 65 around the body of the casing to deaden the sound, and turns of wire 32 are interposed between the sheet and body to form an air-space 33 and further assist in preventing noise. These wires not only hold the asbestos 70 away from the body to form the air-space, but they also strengthen the body, and smaller wire 34 is wrapped around the outside of the sheet to hold the same in place. In Fig. 2 the asbestos is shown as wrapped around the 75 body in contact therewith, the wires 32 being omitted.

Having thus fully described my invention, what I claim is—

1. In an exhaust-muffler, the combination of 80 a casing having an inlet-opening, a conical deflector opposing the inlet-opening and a tubular exhaust member forming means for securing the deflector in place and provided with openings in its side and an open outer 85 end for the escape of the exhaust.

2. In an exhaust-muffler, the combination of 90 a casing consisting of a body portion and opposing heads engaging said body provided with an inlet-opening, a conical deflector with- 95 in the casing adjacent to the inlet-opening and opposing the same and means for securing the heads to the body and for holding the deflector in place consisting of a tubular exhaust member opening through one of said heads and provided with openings in its sides.

3. In an exhaust-muffler, the combination 100 with a casing having an inlet and an exhaust passage, of a deflector within the casing provided with a conical side adjacent to the inlet and dividing the space within the casing into a relatively small and a large chamber with a restricted passage between its outer edge and the wall of the casing connecting said chambers.

4. In an exhaust-muffler, the combination 105 with a casing provided with an inlet at one end and an outlet at its opposite end, of a member supported within the casing near the inlet end thereof with a narrow passage between its outer edge and the wall of the casing and dividing the casing into two chambers of unequal capacity.

5. In an exhaust-muffler, the combination 115 with a casing provided with an inlet at one end and an outlet at its opposite end, of a conical deflector supported within the casing adjacent to the inlet with its apex in the axis of the inlet-opening and with a narrow passage between its outer edge and the wall of the 120 casing.

6. In a muffler, the combination of a casing 125 consisting of a body portion and opposing heads having an inlet-opening, a conical deflector supported within said casing adjacent to the head having the inlet-opening with a restricted passage between its edge and the wall of the body, and a tubular exhaust mem-

ber having openings in its sides between the deflector and the other head and opening through said head.

7. In a muffler, the combination of a casing provided with an inlet-opening, a conical deflector supported within said casing with a narrow passage between its edge and the wall of the casing and opposing the inlet-opening, a tubular exhaust member provided with openings in its sides and having an open end extending through the casing and engaged and closed by the deflector at its opposite end.

8. In a muffler, the combination of a casing consisting of a body portion and heads engaging said body, one of which heads is provided with an inlet-opening, a conical deflector opposing the inlet-opening and secured to the head provided with said opening, a tubular exhaust member provided with openings in its side and secured at one end to the deflector and at its opposite end to the head opposing that to which the deflector is secured to secure the heads to the body.

9. In a muffler, the combination of a casing consisting of a body portion and opposing heads, one of which is provided with an inlet-opening, a conical deflector supported within the casing adjacent to the head having the inlet-opening with a narrow passage between its edge and the wall of the casing, an exhaust-tube having openings in its side secured at its inner end to the deflector and at its open outer end within an opening in the head of the casing, and bolts to hold the heads in engagement with the body and support the deflector.

10. In an exhaust-muffler, the combination with a cylindrical casing having an inlet and an exhaust opening, of a covering of non-combustible material for said casing, and turns 40 of wire interposed between the casing and covering to form an air-space.

11. In an exhaust-muffler, the combination of a cylindrical casing consisting of a body portion formed of sheet metal and heads to engage the body provided with an inlet and an exhaust opening, a sheet of non-combustible material wrapped around said body, and

wire bands interposed between the sheet and body to strengthen the body and form an air-space.

12. In an exhaust-muffler, the combination of a cylindrical body portion, a head to receive one end of the body and provided with an axial inlet-opening, a head to receive the opposite end of said body and provided with an axial screw-threaded opening, a circular deflector supported within the casing with a narrow passage between its edge and the wall of the body and formed with a conical side opposing the inlet and with a screw-threaded socket at its opposite side, an open-ended tubular exhaust member screw-threaded at its opposite ends to engage the socket on the deflector and the screw-threaded opening in the head and having openings in its side, and bolts secured 65 at their inner ends to the deflector and extending through the head having the inlet to hold the heads and deflector in place.

13. In an exhaust-muffler, the combination of a casing consisting of a body portion and 70 heads engaging the ends of said body, one of which heads is provided with an inlet-opening, and a tubular exhaust member provided with openings in its side attached at one end to the head having the inlet and secured to 75 and opening through the opposite head at its opposite end to secure the heads to the body.

14. In an exhaust-muffler, the combination of a casing consisting of a body portion and heads engaging the ends of said body, one of which heads is provided with an inlet-opening, means in the casing adjacent to the inlet-opening and in the path of the incoming exhaust for dividing and spreading said exhaust, and a tubular exhaust member having openings in its side, supporting said means and opening through the casing-head.

In testimony whereof I affix my signature in presence of two witnesses.
